UNITED STATES PATENT OFFICE.

TOICH NAKAHARA, OF NEW YORK, N. Y.

ELECTRIC DOOR-OPERATOR.

957,572.

Specification of Letters Patent. Patented May 10, 1910.

Application filed February 2, 1910. Serial No. 541,453.

To all whom it may concern:

Be it known that I, TOICH NAKAHARA, a subject of the Emperor of Japan, and resident of the borough of Manhattan, in 5 the city and county of New York and State of New York, have invented certain new and useful Improvements in Electric Door-Operators, of which the following is a specification.

10 This invention relates to a means for causing a door to be mechanically opened and closed by an electric motor operating to open it, and a weight tending to overhaul or reverse the motor thus operating to close it, 15 and although approximations of this device have been known and developed in the past many of my best and most advantageous features were not a part of such approximations.

20 I utilize the motor itself as the means for retaining the door in an open position, by the action of a fully magnetized field exerting its retarding and holding force upon a short circuited armature. This 25 principle is well known in electric traction apparatus and in elevators and hoists.

The principal features and advantages of my invention will develop in the specification and what I consider a desirable means 30 of carrying out this invention follows in which:

Figure 1 is a diagrammatical view partly in elevation, of the complete apparatus and a door in connection with which is operates. 35 Fig. 2 is on a larger scale it shows the field opening and closing switch.

Similar letters of reference indicate like parts wherever they appear.

As shown in the drawings, my device is 40 designed to operate with a sliding door and such a door is shown at A in Fig. 1. The door is, by the brackets A¹ and the rollers A² supported upon a track B, which is in turn attached to a convenient support B¹ 45 which may be the side wall through which the door opening has been produced. The ordinary means as a handle A⁴ is provided for opening the door by hand and the closing means is secured to the door at a high 50 point, in this instance at A³. A weight C secured to the downwardly hanging end of the cable C¹ is the closing means, the cable passes over the pulley C² and is attached to the door at A³. The pulley C² 55 is rotatably mounted in a bracket C³, which bracket is in turn secured to a convenient

though stationary support, which may be the side wall or partition. At a convenient height, but to the edge opposite to that which the cable C¹ is attached, a cable E⁵ 60 is secured by means of a bolt or by other means. A motor of proper size to perform the duties required, is arranged by being secured to the side wall or other firm support, at a just sufficient height to allow the 65 cable E⁵, which is to be attached to the drum E⁶ on the motor, to travel in a horizontal plane.

A plurality of switches which I will describe in detail later in the specification, 70 I have shown as secured to the floor and immediately below the motor. They must be placed in line with the travel of the door, so that a projection A⁵, which is also attached to the right edge of the door will 75 contact with the switches for a purpose which shall appear later.

A portion of the floor which I have indicated by K¹, forms a hinged platform, to give an easy and not too great movement 80 to the platform, I prefer to have this platform as wide as the door and have in my experiments hinged the whole section of the floor, which is immediately below the door, when the door is in its closed position. 85

The electrical and electro-mechanical part of my device is somewhat complicated so I will describe them by following the path of the current commencing with the uppermost line lead D, which is directly connected to a 90 block D¹ which carries a contact screw D². A spring switch D³ is normally in contact with the screw D² and receives current from the line lead D. An armature lead E¹ of the shunt-wound motor E is connected to the 95 spring switch D³, and with one brush of the motor E. The other brush is, through the armature lead E² connected to the spring switch F² and this spring switch is in normal contact with a contact-screw F¹ carried 100 by the block F. A lead G¹, one end of which is connected to the block F, has its other end attached to the stationary part of a spring switch G.

G² indicates the spring or flexible member 105 of the switch and to this member G² a lead H is attached. This lead H is the other line lead, the spring G is normally in an open condition.

The fields of the motor E are connected 110 independent of the armature circuit or switches. One of the field leads E³ is di-

rectly connected to the line lead D, the other lead E⁴ is carried to a switch J located at a low point adjacent to the lower left corner of the door. The switch is secured 5 to the jamb of the door and its action will be described later in the specification.

The floor K has a section K¹ in the shape of a trap or movable platform hingedly connected to the main floor K and extending 10 under the door for the full width of the door sill. A spring K³, which is an ordinary coil spring of sufficient strength retains the trap K³ in an upward position level with the remainder of the floor, but when a 15 weight as that of a person passing through the door is placed upon the trap K¹ it causes one end of the trap to sink and brings the projection K² into contact with the flexible member G² of the switch G with the result 20 that the circuit is closed through the switch, and through the line lead H and lead G thus to the armature. Another result of the depressed platform is that the blade J¹ of the switch J is forced into contact with the 25 terminal J² thus closing the field circuit of the motor E through the wire J³ and the field lead E⁴. The motor revolves and the cable E⁵ is wound upon the drum E⁶ drawing the door into an open position, this 30 continues until a projection A⁵ on the door A strikes the spring switch F² and forces it out of contact with the screw F¹. The spring switch F² barely leaves the screw F¹ when it comes into intimate contact with the 35 spring switch D³ through the close proximity of the blocks F⁴, D⁴. The spring switch D³ is forced out of contact with the screw D² and the armature circuit is open and the armature stops revolving. It will 40 be seen that as soon as the armature circuit is open, the armature is disconnected from the line, but almost at once the armature circuit is closed again upon itself, that is, it is short circuited. The field circuit remains complete 45 and should the motor overhaul by the action of the weight C and thereby pay out the cable E⁵ to any extent, the projection A⁵ leaves the spring switch F² and the armature circuit is immediately completed, with the 50 result that the motor will again start and rewind the cable, this will occur as often as it is necessary to accomplish the result of retaining the door in an open position while a person is on the platform A¹. 55 It is sometimes desirable to cause the door to close slowly. I accomplish this by keeping a full field, or a complete field circuit through the motor even after a pedestrian has left the platform K¹, in fact until the 60 projection A⁶ comes in contact with the adjustable block J⁴ on the operating shaft J⁵, of the switch J.

The door closes through a greater or less portion of the entire length of travel at the 65 slow rate allowed by reversing the armature

in a full field, until the projection A⁶ strikes the block J⁴ and moves it forward through a sufficient distance to cause it to lift the blade J¹ from the terminal J², of the switch J thus opening the field circuit, after which 70 the motor will run in reversed direction only retarded by the friction of the bearings.

Modifications may be made within the scope of the appended claims without departing from the principles or sacrificing 75 the advantages of this invention.

The field switch J¹ and its connections may be dispensed with, the field connection E⁴ being made with the block F or the stationary side of the switch G, this will cause 80 the door to close more rapidly which may be an advantage in some instances.

This device may be worked as well on a swinging door.

Other modifications may be made by a 85 good mechanic.

Having carefully and fully described my invention what I claim and desire to secure by Letters Patent is:

1. In a device of the character described, 90 a door, a motor for operating said door, a flexible connection between said motor and said door, a weight arranged in opposition to said motor and flexibly connected to said door, a hinged platform beneath said door 95 and a switch operated by said platform for starting said motor, means attached to said door for causing the motor to stop, and a double contact switch operated by said last named means for causing the motor to exert a holding motion upon said door.

2. In a device of the character described, in combination with a door, a motor for opening such door, a weight arranged in opposition to such motor for closing said 105 door, means arranged below said door for automatically starting said motor, and an automatically operated switch for stopping said motor, said switch arranged to short circuit the armature circuit by continuation 110 of the movement that stops the motor.

3. In a device of the character described, in combination with a door, a motor, a weight arranged in opposition to such motor, means below said door for starting said 115 motor, an automatically operated switch for stopping said motor and short circuiting the armature thereof, and an additional switch for closing the field of said motor and maintaining it closed until the door has reached a predetermined point in its closing motion.

Signed at New York city in the county of New York and State of New York this 25th day of January A. D. 1910.

TOICH NAKAHARA.
